UNITED STATES PATENT OFFICE

WILLIAM H. ROBERTSON, OF DAYTON, OHIO, ASSIGNOR, BY MESNE ASSIGNMENTS, TO THE NATIONAL CASH REGISTER COMPANY, OF DAYTON, OHIO, A CORPORATION OF MARYLAND

CASH REGISTER

Application filed July 9, 1925. Serial No. 42,512.

This invention relates to accounting machines and the like, the primary object being to devise a mechanism which is adapted to be placed in the house in a convenient position to be used by all members of the household in recording the various expenditures entering into the maintenance of the house and its members.

Another object is to provide a machine that will accumulate items and display a total of the items.

Another object is to provide a classified record strip upon which entries may be made of the various household expenditures.

Another object is to provide a convenient receptacle in which to place receipts received on household expenditures.

With these and incidental objects in view, the invention includes certain novel features of construction and combinations of parts, the essential elements of which are set forth in appended claims and a preferred form or embodiment of which is hereinafter described with reference to the drawings which accompany and form part of this specification.

Of said drawings:

Fig. 1 is a plan view of the register with the greater part of the cabinet broken away and a portion of the totalizer mechanism shown in section for clearness.

Fig. 2 is a right hand elevation of the register showing the container for receipts.

Fig. 3 is a sectional view taken on the line 3—3 of Fig. 1, looking in the direction of the arrows, and showing a totalizer wheel and the index lever mechanism.

Fig. 4 is a sectional view taken on the line 4—4 of Fig. 1, looking in the direction of the arrows, and showing the full stroke mechanism for the driving shaft.

Fig. 5 is a detail view showing the totalizer wheels locking plate and the transfer pawls.

Fig. 6 is a top plan view of the index plate and levers.

Fig. 7 is a front elevation of the totalizer mechanism with parts omitted for clearness.

Fig. 8 is an enlarged sectional view taken

on the line 8—8 of Fig. 7, looking in the direction of the arrows.

Fig. 9 is a detail view showing a portion of a totalizer wheel and index lever plate.

Fig. 10 is a detail perspective view showing a portion of an index lever and plate.

Fig. 11 is an enlarged detail view of a portion of the totalizer transfer pawl mechanism.

Fig. 12 shows two totalizer wheels and a transfer device before a transfer takes place.

Fig. 13 shows the same two wheels and the transfer device after a transfer has been made.

Fig. 14 is a time chart for the two cams on the main shaft.

General description

Described in general terms the machine is a small portable register adapted to be placed on a stand or hung on the wall in a house, where it may be used by the various members of the family or servants in recording household expenditures.

The machine includes a classified record strip of paper upon which entries are made of the various items for which money is paid out. The items recorded on the record strip may be set up by index levers for accumulating the amounts in a totalizer when an operating crank is given a cycle of movement.

A small receptacle in the form of a drawer provides a convenient filing place for receipts received from the various expenditures.

Specifically described, the machine includes a frame 30 (Figs. 1 and 2) provided with an ear 31 formed at right angles thereto. This ear supports a rod 32 upon which is freely mounted a supply roll of record paper 33. This paper is wound upon a wooden core 34 and rotates against the friction tension of a disk 35 and a spring 36. This supply roll is adapted to be rotated by a knurled knob 37 which has two pins 38 penetrating the wooden core 34. The supply roll and knurled knob are held in position on the rod 32 by a screw 39.

The paper is unwound from the supply roll 33 and wound onto a receiving roller 43 freely mounted upon a stud supported at one end by an ear 44 formed on the frame 30. This receiving roller has at its right hand end a disk 45 to guide the paper as it is wound upon the roller. A spring 46 intermediate the disk 45 and the ear 44 provides a friction tension on the roller in its 10 rotating movement. The end of the paper is secured to the receiving roller 43 by being placed between a rod 47 and the roller in the usual manner. The rod is supported at its left hand end in a boss 48 projecting 15 from a knurled knob 49. The paper is wound upon the receiving roller by turning the knurled knob 49, and when it be desired to unwind the paper from the receiving roller to review items entered upon the 20 record strip, the operator turns the knurled knob 37 of the supply roll. The paper is always held taut by the tension springs 36 and 46, previously described.

As the record strip passes from the supply 25 roll to the receiving roller it moves over a writing table 50 (Fig. 2) supported by the frame of the machine. Referring to Fig. 1 it may be seen that the record strip is supplied with ruled lines so that the entries may 30 be made in their proper columns according to a classified index plate 51 which is secured to a casing 52 enclosing the mechanism of the machine.

Totalizer

The various items entered upon the record strip may also be accumulated in a totalizer which furnishes a reading total of the expenditures. This totalizer is placed at the 40 top of the machine and consists of a plurality of wheels. Each of the wheels includes a circular band 58 upon which are engraved three groups of digits. The band is fastened to a formed disk 59 (Fig. 1) secured to a 45 hub 60 by a collar 61. Secured to the disk 59 by rivets 62 is a disk 63 provided with a plurality of elongated openings 64 (Fig. 8) equal in number to the digits on the band 58. Loosely fitted in each of these elongated 50 openings is a slidable projectable stop 65 (Figs. 1, 8 and 9). The right hand end of the stop 65 is guided by an opening 66 formed in the disc 59 of the totalizer wheel (Figs. 3 and 9). These stops are adapted 55 to be moved laterally by means which will hereinafter be described. Each stop is provided with shoulders to arrest it in its home and operated positions.

A spring clamp 67 (Figs. 8 and 9) is 60 adapted to retain the stop 65 in either its home position or operated position. This spring clamp is positioned between the disk 59 and the disk 63.

The totalizer wheels are freely mounted 5 upon a shaft 68 supported at the right hand

end by a bracket 69 fastened to the frame of the machine, and at the lefthand end by a bracket 70 which is also secured to the frame of the machine. The shaft 68 is provided with two grooves 71 (Figs. 1, 3 and 8) 70 formed on opposite sides of the shaft and running in the direction of the length of the shaft. Slidably and non-rotatably mounted on the shaft 68 are disks 72 placed between the hubs 60 of the totalizer wheels. These disks have two lugs 73 (Figs. 3 and 8) which are loosely fitted in the grooves 71 in the shaft 68. Near the left-hand end of the shaft 68 (Fig. 1), and contacting the last disk 72, is a sleeve 77 loosely fitted on the shaft and constantly forced toward the disk 72 by a compression spring 78 entwined about the shaft 68. The function of this spring is to furnish a sufficient friction between the disks 72 and the hubs 60 of the totalizer wheels to cause these wheels to rotate with the shaft until they meet with an obstruction which will hereinafter be described. The amount of compression of the spring 78 is controlled by an adjusting nut 79 applied to the left hand end of the shaft 68. This nut is retained in adjusted position by a pin 80.

The shaft 68 is rotated by a manually operated crank 81 (Figs. 1, 2 and 6) pinned to the right hand end of the shaft and projecting to the outside of the casing of the machine. This operating crank is turned in the direction of the arrow, shown in Fig. 2, and is prevented from retrograde movement by a ratchet wheel 82 (Fig. 4) pinned to a drum cam 83 secured to the shaft 68. Co-operating with the ratchet wheel 82 is a spring-actuated pawl 84, pivoted on a stud 85, supported in a bracket 86, projecting upwardly from the frame of the machine.

The amount of rotation of the totalizer wheels is predetermined by a plurality of index levers 90 adjacent to each of the wheels. Each index lever is mounted on a hub 91 loosely fitted on the hub 60 of a totalizer wheel (Fig. 1). A spacing collar 92 is provided to maintain the index levers in their lateral positions with a sufficient working clearance between the hubs of the levers and the totalizer wheels to permit the levers to be moved independently of the wheels. Integral with the index lever 90 is a notched plate 93 (Fig. 8), which cooperates with a spring actuated pawl 94 to retain the index lever in its various set positions. This pawl is freely mounted upon a stud 95, supported in a bracket 96, secured to the frame of the machine. The index levers protrude through a slotted indexing plate 97 (Figs. 6, 7 and 8), which has a plurality of sets of digits engraved parallel with the slots. Fastened to each lever is a guiding pointer 98 to assist the operator in properly selecting the desired digits.

The indexing plate 97 is also provided with round openings 99 through which a reading of the totalizer wheels may be taken. The indexing plate is supported at both ends by brackets 100 and 101 secured to the frame of the machine and held in place by screws 102 engaging elongated openings in the plate. These elongated openings permit the indexing plate to be moved laterally by a cam groove 103 (Figs. 1 and 7) cooperating with a roller 104 mounted on a stud fastened in the indexing plate. The lateral movement of the indexing plate occurs near the beginning of the operation of the crank 81, the plate being moved toward the right and then immediately returned to home position. The timing for this cam 103 is shown in Fig. 14.

Tappets 108, (Fig. 10) are provided with openings through which the levers 90 extend, and are adapted to be moved differentially with the levers in the slots formed in the indexing plate 97 and also are adapted to be moved laterally by the plate 97. Each tappet 108 is guided in the slot of the indexing plate 97 by a flange 109 and a stud 110. The opening in the tappet 108 through which the lever 90 extends is of sufficient width to permit the tappet 108 to move laterally with the indexing plate 97 without any lateral movement of the lever 90. The tappet 108 (Figs. 9 and 10) has a downwardly extending flange 111 which is placed in alignment with one of the various projectable stops 65 by the index lever, and as the operating crank 81 is turned, and the indexing plate 97 moves laterally to the right, the flange 111 will engage the stop 65 and move the latter toward the right until its right hand end projects out a sufficient distance to act as a stop for the totalizer wheel as it comes into contact with a shoulder 112 (Figs. 5 and 8) of a pivoted lever 113. As the stop 65 engages the shoulder on the lever 113, that particular wheel will cease to move with the shaft 68 in its cycle of operation. For example, if an index lever is moved into alignment with the digit "three," the stop 65 in alignment with the flange 111 is projected out of normal position and the totalizer wheel rotates with the shaft 68, by the friction disk previously described, until the stop contacts the shoulder 112, (Fig. 12) which permits three divisions of movement of the wheel, as previously stated. Each totalizer wheel is provided with three sets of digits which affords ample time in a single cycle of rotation of the shaft 68 to operate the various devices prior to and after the movement of the totalizer wheels when they move their greatest extent, which is ten divisions of movement.

As a totalizer wheel moves from "nine" to "zero," it is necessary to carry "one" to

the wheel of next higher order. For this purpose three brackets 114 (Fig. 8) are secured to each digit wheel. Any one of these brackets may engage the lower end 115 of the lever 113 (Figs. 5, 8, 12 and 13) and move this lever in a clockwise direction from the position shown in Fig. 12 to the position shown in Fig. 13, thus moving the shoulder 112 out of the path of the projected stop 65 carried by the totalizer wheel. With this lever out of the path of the stop 65, the totalizer wheel is permitted to move an additional step (from position in Fig. 12 to position in Fig. 13) during the rotation of the shaft 68, when it is stopped by the projected stop 65 engaging a shoulder 116 (Fig. 5) formed on an arm 117 projecting from a laterally sliding bar 118 guided by two studs 119 fastened in a bracket 120 secured to the frame of the machine.

The tripped transfer levers 113 are restored to their normal positions at the beginning of the operation of the machine by pins 125 (Fig. 5) mounted in downwardly extending arms 126 of the indexing plate 97. These pins engage the ends 115 of the levers 113 (Figs. 5 and 8) as the indexing plate 97 (Fig. 6) is moved toward the right by the cam groove 103 (Fig. 1) previously described.

The transfer levers 113 are retained in either their home positions or their operated positions by tension springs 121 (Figs. 8 and 11). These springs are each in the form of a split ring and each encircles the cone-shaped head of a pin 122 secured by its opposite end to the transfer lever 113. Each spring 121 is slightly expanded in placing it in position so that its closing-in action against the cone will cause a downward pressure on the pin 122, thereby creating friction between the under side of the transfer lever 113 and the top of a sleeve 123 secured in the bracket 120.

The totalizer wheels are normally locked against rotation by projections 127 (Figs. 1 and 5) formed on the arms 117 entered into slots 128 (Figs. 1 and 3) formed in the totalizer wheels. The bar 118 (Figs. 1 and 5), with which the arms 117 are integral, is moved laterally by a cam groove 129 (Fig. 1) cooperating with a roller 130 mounted on a stud fastened in said bar. The cam groove 129 is formed so as to move the projections 127 from the position shown in Fig. 7 to the position shown in Fig. 12 to unlock the totalizer wheels at the beginning of the operation of the crank 81 and then move these projections 127 from the position in Fig. 12 to the position in Fig. 7 to again lock said wheels near the end of the operation. The timing for this cam 129 is shown in Fig. 14.

As the bar 118 returns to home position to lock the totalizer wheels, the arms 117 will simultaneously engage the projected stops

65 (Figs. 8 and 9) and return them to home positions.

The machine is provided with a sliding drawer 136 (Figs. 1 and 2) which furnishes 5 a convenient place in which to file receipts received from the various monetary transactions. Access to this drawer is had by sliding the drawer toward the right by the aid of a finger grip 137.

10

Operation

In using the machine for the purpose for 15 which it is intended, when money is paid for household items coming under the various classifications, as shown by the record strip index plate in Fig. 1, the proper entries are made upon the record strip. As the exposed portion of the record strip is 20 filled with entries the knob 49 of the upper or receiving roller is turned to move additional unused record material into writing position. To review entries which have 25 been moved ahead of the writing position or out of view, the lower knob 37 is turned in a reverse direction.

After entering the items upon the record strip, corresponding items or amounts are 30 set up by the index levers 90, (Fig. 6) after which the operating crank 81 is given one cycle of movement to enter the item or 35 amount in the totalizer. The total accumulated can be read at any time through the openings 99 provided for that purpose. The totalizer wheels may be reset to zero at any 40 time by moving the index levers 90 to the digits on the indexing plate 97 corresponding to the complement of the digits on the totalizer wheels showing through the openings 99 and then operating the crank in the 45 usual way. The customary receipt received when paying out money may be filed in the drawer or receipt compartment designated "Receipts" in Fig. 2.

While the form of mechanism herein 50 shown and described is admirably adapted to fulfill the objects primarily stated, it is to be understood that it is not intended to confine the invention to the one form or embodiment herein disclosed, for it is susceptible of embodiment in various forms all coming within the scope of the claims which follow.

What is claimed is:

1. In a machine of the class described, 55 a casing, a totalizer element, a movably mounted cover plate for the totalizer element, stops movably mounted in said element, and means operated by said cover plate for projecting any selected stop into 60 functioning position.

2. In a machine of the class described, the combination of a casing, a totalizer element, a movably mounted cover plate, movably mounted stops for said element, means for 65 selecting the stops, and means operated by

said plate for moving the selected stop into functioning position.

3. In a machine of the class described, the combination of a totalizer wheel, a shaft supporting said wheel, equidistantly spaced 70 slides mounted on said wheel, a differentially movable value determining device pivoted on said shaft, and means operable under control of said value determining device for moving the adjacently located slide 75 into functioning position.

4. In a machine of the class described, the combination of a totalizer wheel, a shaft supporting said wheel, equidistantly spaced 80 stops movably mounted on said wheel, a differentially movable value determining device mounted on said shaft, a stop operating member movable differentially with 85 said value determining device and means to shift said stop operating member to move a stop into functioning position.

5. In a machine of the class described, the combination of a totalizer wheel, stops movably mounted in said wheel, indexing means, 90 and means for projecting a stop occupying a position corresponding to the amount indexed, into functioning position.

6. In a machine of the class described, the combination of an indexing lever, a member carried by said lever mounted for 95 relative movement thereto laterally, a slotted plate guiding said member, and means for moving said plate to shift said member laterally relatively to said lever.

7. In a machine of the class described, 100 the combination of a totalizer wheel, stops movably mounted in said wheel, a differentially movable indexing member, a plate provided with a slot in which said indexing member moves, stop actuating means guided in said slot and movable differentially 105 with but laterally relatively to said indexing member, and means for operating said plate for moving a selected one of said stops into functioning position.

8. A totalizer wheel comprising two disks 110 and a rim defining an annular chamber, said disks being provided with aligned slots opening laterally from said chamber, and members within said chamber slidably 115 mounted in said slots.

9. A totalizer wheel comprising two slotted disks together defining a peripheral channel, the slots being shorter than the depth of said channel, a rim closing said 120 channel to define an annular chamber, slides in said chamber projecting into said slots, and shoulders on said slides for retaining 125 said slides within said channel and for limiting their movements into home and operated positions.

10. In a machine of the class described, the combination of a totalizer wheel, movably mounted stops carried thereby, means for selecting a stop for controlling the dif- 130

ferential movement of said wheel, a slid-
5 eral bar, means carried by said bar to arrest the
selected stop and to hold said wheel in ad-
justed position, and to return said selected
stop to normal position, and means for slid-
ing said bar.

11. In a machine of the class described,
the combination of a totalizer wheel, mov-
ably mounted stops carried thereby, means
10 for selecting a stop for controlling the dif-
ferential movement of said wheel, a slid-
able bar, a single member carried by said bar
adjacent the wheel to arrest the selected stop
15 and to hold the wheel in adjusted position,
and to return the selected stop to normal
position, and means for sliding said bar.

12. In a machine of the class described,
the combination of a rotatable shaft, means
20 for operating said shaft, a totalizer wheel
freely mounted on said shaft, a hub on said
wheel, an index lever freely mounted on the
hub of the wheel, a friction connection be-
25 tween the totalizer wheel and the shaft, and
means controlled by said index lever for
stopping said totalizer wheel in a position
determined by the adjustment of the index
lever.

13. In a machine of the class described,
the combination of a rotatable shaft, means
30 for operating said shaft, a totalizer wheel
freely mounted on said shaft, and index
lever adjacent said totalizer wheel and
mounted in axial alinement therewith, fric-
35 tion means to drive the totalizer wheel from
the shaft, means controlled by the index
lever for stopping said totalizer wheel, and
means operated by said operating means for
locking said totalizer wheel in the various
positions of adjustment.

40 14. In a machine of the class described,
the combination of a rotatable shaft, means
for operating said shaft, a totalizer wheel
rotatably mounted on said shaft, means for
differentially controlling the extent of rota-
45 tion of said totalizer wheel, a laterally move-
able means normally engaging said totalizer
wheel to prevent rotation of the same, and
a cam secured to said shaft adapted to dis-
engage said laterally movable means from
50 said totalizer wheels at the beginning of the
operation of said shaft and to engage the
laterally movable means with the wheels
near the end of the operation.

15. In a machine of the class described,
55 the combination of a rotatable shaft, means
for operating said shaft, a totalizer wheel
rotatably mounted on said shaft, an index
lever adapted to be moved differentially, a
tappet moving with said lever and adapted
60 for lateral movement relatively to said lever,
slid-able members mounted in said wheel and
adapted to be adjusted from normal position
to operated position by said tappet, and
means adapted to engage said adjusted slid-
65 able members to stop rotation of said wheel.

16. In a machine of the class described,
the combination of a rotatable shaft, means
for operating said shaft, a totalizer wheel
70 rotatably mounted on said shaft, a plurality
of groups of digits arranged on the periph-
ery of said totalizer wheel, a plurality of
movable members equal in number to the
digits and supported in said totalizer wheel,
means having a home position and an op-
erated position cooperating with said mov-
able members to form a variable stop for
said wheel, and a plurality of means carried
on said wheel adapted to operate said last-
mentioned co-operating means.

75 17. In a machine of the class described,
the combination of a totalizer wheel, mov-
able stops carried thereby, means for selec-
tively projecting said stops, and a member
co-operating with said wheel comprising a
stop portion cooperable with the project-
ed one of said first mentioned stops, a por-
tion for returning said projected stop to
home position, and a portion for holding
said wheel in adjusted position.

80 18. In a machine of the class described,
the combination of a totalizer wheel; stops
movably mounted in the wheel; means to
select any of the stops to control the differ-
ential travel of the wheel; an abutment
90 normally lying in the path of the selected
stop to arrest the differential travel of the
totalizer wheel; means to return the select-
ed stop to normal idle position and to hold
the wheel in its differentially adjusted pos-
ition; and means to shift the last-named 100
means into and out of effective position.

In testimony whereof I affix my signature.
WILLIAM H. ROBERTSON.
